UNITED STATES PATENT OFFICE.

FLOYD F. COLE, OF MANSFIELD, OHIO, ASSIGNOR, BY MESNE ASSIGNMENTS, TO ELITE MANUFACTURING COMPANY, A CORPORATION OF OHIO.

VEHICLE JACK.

Application filed November 18, 1927. Serial No. 234,072.

My invention relates to an improvement in vehicle jacks, of the ratchet type, and the object of the invention in general is to provide a simple and inexpensive but durable 5 jack structure which may be readily assembled and easily operated. Thus the standard and other parts of the jack are made of pressed steel, and the main lift member is provided with a hinged extension of pressed 10 steel which is particularly constructed to provide stability and a firm support for the load when folded to a position of use over the head of the lift member. A forked member of pressed steel and a bent leaf spring also forms 15 a part of the assembly to control the operation of the ratchet mechanism and the lifting and lowering movements of the lift member, and the said forked member and spring are particularly constructed to permit convenient 20 and rapid assembly of the jack parts and to function positively and safely in the different positions in which they are set to effect raising or lowering movements of the load.

In the accompanying drawings, Fig. 1 is a 25 vertical section centrally through my improved jack showing the operating parts in the act of raising the toothed rack or lift member, and Fig. 2 is a rear elevation of the jack with the lift member in the same position 30 and the handle and head in section. Fig. 3 is a horizontal section of the jack on line 3—3 of Fig. 1. Fig. 4 is a side view, enlarged, of the spring and forked member for controlling the pawls, and Fig. 5 is a view of 35 the same parts from the opposite side thereof, Fig. 6 is a sectional view on horizontal line 6—6 of Fig. 4. Fig. 7 is an end elevation of the spring and forked member shown in Fig. 5, and Fig. 8 is a sectional view vertically on 40 line 8—8 of Fig. 5. Fig. 9 is a perspective view of the spring, and Figs. 10 and 11 are perspective views of the operating pawl and the holding pawl, respectively. Fig. 12 is a sectional view corresponding to Fig. 1 but 45 showing the operating lever raised and the holding pawl engaged with the toothed rack bar or lift member. Fig. 13 is a sectional view corresponding to Fig. 12 but showing the lever lowered and the operating pawl engaged with the rack bar, as in lowering the 50 load. Fig. 14 is a horizontal section of the jack on line 14—14 of Fig. 1.

The jack comprises a ribbed base 2 of 55 pressed sheet steel having vertical border flanges 3—3 to stiffen the same. A hollow

standard 4 of pressed sheet steel is flanged horizontally at its bottom, and the flanges 5 are riveted to the ribs 6 of base 2. Flaring ribs 7 are struck up at an inclination in the flat sides of the standard at the corners of the 60 base flanges to reenforce the same, and a ribbed channel 8 is also struck up, in each flat side wall of the standard parallel with the front cross wall 9. The ribbed channels 8 extend upwardly from the bottom flanges 5 65 to within a short distance of the top of the standard, and lateral projections 10 at the lower end of the rack or lift bar 11 extend into the ribbed channels 8 to guide the bar and to hold it slidably within the standard. Pro- 70 jections 10 are preferably formed by upsetting the stock or crowding the metal laterally under pressure at the lower end corners of bar 11. In this way the flat side 12 of bar 11 is supported to slide against the cross wall 75 9 of the standard, and the top edge of each side wall of the standard is also indented at the point 14 opposite the corner edges of the ratchet teeth 15 thereon to prevent lift bar 11 from tilting. A part of the top of the 80 standard is also closed by inwardly extending flanges 16 which meet and are rigidly held in bracing relation by rivets 17 which pass through the side walls of the standard.

The rear end of the standard is open to receive the operating mechanism comprising a forked socket member 18 for a removable handle 19. Socket member 18 is pivotally supported upon a cross pin or bolt 20, which also supports a holding pawl 21 pivotally opposite 85 the teeth on rack bar 11. The inner forked ends of socket member 18 carry an operating pawl 22, and the said pawls are pressed U-shaped in cross section and formed with depending prolongations or tails 21' and 22', 90 respectively. Mounted immediately beneath the said pawls is a pivoted lever 23 and a tilting device 24 carrying a leaf spring 25 for controlling the working movements of said pawls. The spring is bent into U-shape to 95 provide two upright spring arms 26 and 27 and an irregularly curved connecting base portion 28. The upper free ends of the spring arms are adapted to press constantly against the depending prolongations or tails 21' and 22' of the two pawls, and the cross connecting portion 28 of the spring is detachably interlocked with a horizontal finger 29 centrally at the bottom of tilting device 24, see Figs. 4 and 5. This tilting device is a 100 105 110

simple sheet metal stamping having a right-angled projection 30 at one bottom corner which is perforated to permit the device to be pivotally supported within the standard upon 5 a cross pin 31, and the opposite corner of this stamping is formed with a second projection 32 which is bent in an inclined plane to permit a crank arm 33 on pivoted lever 23 to engage the same and to tilt said device when 10 said lever is turned outwardly and upwardly as seen in Figs. 1 and 2. The upper part of the tilting device 24 is forked to provide two beveled arms 34 and 35, each of which is bent to bring the pointed or beveled end portions 15 thereof in the same vertical plane as that occupied by the arms 26 and 27 of the leaf spring when said spring is attached to device 24, i. e., when the bow 28 is interlocked with finger 29 and part 36 of the bow is seated upon 20 projection 30. In this way each spring arm is held under constant tension and presses yieldingly against the beveled edges of said arms 34 and 35 when the spring is connected with tilting device 24, and the tails 21' and 22' 25 of the pawls are free to enter the flaring spaces between the spring arms and the beveled arms when the jack handle is oscillated. The downward movement of the handle effects a lifting movement of the rack bar 30 and the load, providing the crank member or lever 23 is first turned upwardly to a horizontal position as shown in Fig. 1. In that setting pawl 22 is pressed by the spring arm 27 to engage one of the teeth on rack bar 11, 35 and the holding pawl 21 is pressed by spring arm 26 to engage a tooth higher up on the rack bar. As the jack handle is pressed downwardly the operating pawl 22 raises the rack bar and the load, and the holding pawl 40 21 drops under a tooth and sustains the bar and load in the elevated position, an operation which may be repeated intermittently until the limit of upward movement of the rack bar is reached as fixed by the projections 10 on 45 the bar and the length of the ribbed channel 8 in the standard. To lower the load a different setting of the tilting device 24 is required, which is obtained by pressing the lever or crank member 23 down to a vertical position as shown in Figs. 12 and 13. In that setting the leaf spring 25 constantly tends to 50 tilt device 24 upwardly on its pivot and to move the beveled arms relatively nearer the rack bar so that when the jack handle is lowered pawl 22 will be caused to engage a tooth on the rack bar to lift the bar and the load slightly until the holding pawl 21 is released from its tooth, whereupon the holding pawl 55 will swing away from the rack bar because beveled arm 34 is now pressing against tail 21' of the holding pawl as shown in Fig. 13. Holding pawl 21 is held in this retired or 60 release position for a brief interval until the load is lowered a step or two, but when tail 22' 65 of operating pawl 22 descends and rides over

beveled arm 35 the tilting device 24 is turned on its pivot by the pressure of tail 22' and the beveled arm 34 moves away from tail 21' of pawl 21 and permits the spring arm 26 to throw the holding pawl 21 into stop and locking engagement with a tooth on rack bar 11, see Fig. 12. To more clearly illustrate the working relationship of the parts I show the jack handle at its extreme high and low positions in Figs. 12 and 13, but such an extreme are movement or sweep of the handle is not actually required to lower the rack bar step by step. 70 75

The load is engaged and supported alternatively by a flanged head 38 or by a hinged yoke 39 at the top of rack bar 11. Head 38 is riveted to the upper end of the rack bar, and yoke 39 is hinged to one end of the head to permit it to swing either to one side of the bar or directly over and upon head 38. 80 85 Yoke 39 is made of sheet steel of relatively light weight, and to give strength and stability thereto to support a heavy load the side walls 40 are pressed inwardly on tapering or conical lines and the apices of the corner 90 brought together in bracing relation and secured together by a single rivet 41. The bottom edges 42 of the yoke overlap the depending side flanges of head 38 and because the side walls of the yoke are indented and united 95 as described the yoke may be seated firmly upon head 38 without danger of displacement or spreading under load. 100

What I claim, is:

1. A vehicle jack, comprising a standard, 100 a toothed bar with said standard, a pair of pawls engageable with said bar, an oscillatory handle mounted on said standard carrying one of said pawls the other of said pawls being mounted on said standard, a device pivoted within said standard having beveled arms, and base projections, a U-shaped spring interlocked with said projections and situated opposite said beveled arms, said spring and beveled projections being engageable 105 with said pawls, and means for holding said pivoted device in an inactive position. 110

2. A vehicle jack, comprising a standard, a toothed bar within said standard, a holding pawl for said bar connected to said standard, an operating handle mounted on said standard having a pawl engageable with said toothed bar, said pawls having prolongations, a forked member pivotally mounted at one end within said standard adjacent said prolongations, said member having a finger at its bottom and an inclined projection at its free end, a U-shaped spring interlocked with said finger having free spring extremities situated opposite the forked portions of said member, and a lever pivoted to said standard having a crank portion engageable with said inclined projection. 115 120 125

3. A vehicle jack, comprising a standard, a rack bar within said standard, a handle on 130

said standard carrying an operating pawl for said rack bar, a holding pawl on said standard for said rack bar, said pawls having prolongations, a device pivoted to said standard having lateral projections at its base and upright beveled prongs engageable with said prolongations, a U-shaped spring having an irregularly shaped connecting portion interlocked with said base projections and having its spring arms extending upwardly opposite said beveled prongs and engageable with the prolongations in said

pawls, and means for tilting and holding said pivoted device in an inactive position.

4. A vehicle jack, comprising a standard, 15 a lift member within said standard, operating mechanism for said lift member mounted upon said standard, a load supporting head affixed to said lift member, and a yoke hinged to said head having interengaging 20 side walls riveted together and adapted to overlap and rest upon said head.

In testimony whereof I affix my signature.
FLOYD F. COLE.
